UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

TICKET-STAPLING MACHINE.

1,159,447.

Specification of Letters Patent.

Patented Nov. 9, 1915.

Application filed July 30, 1914. Serial No. 854,023.

To all whom it may concern:

Be it known that I, HENRY WEBER, a citizen of the United States, residing at Chicago, in the county of Cook and State of Illinois, have invented certain new and useful Improvements in Ticket-Stapling Machines, of which the following is a specification.

This invention relates to ticket stapling machines in general and relates particularly to the placing of staples in tickets for use on clothing and other similar merchandise.

The present machine is designed to pierce the ticket which is fed to the machine in a continuous strip, with a staple and partially clench the legs of the staple under said ticket so that the staple will be held in place in the ticket.

Another object of the present invention is the provision of an adjustable mechanism which will receive the tickets, in a continuous strip, from the stapling mechanism and sever them into individual tickets, said mechanism being adjustable to form tickets of various lengths and sizes.

With the above and other objects in view, this invention consists in the construction, combination and arrangement of parts, all as hereinafter more fully described, claimed, and illustrated in the accompanying drawings, wherein—

Figure 1 is a side elevation of a stapling machine constructed in accordance with the present invention. Fig. 2 is a vertical section taken along the line 2—2 of Fig. 1, and illustrates the cutting mechanism for severing the tickets which are operated upon by the machine in a continuous strip. Fig. 3 is a vertical section taken along the line 3—3 of Fig. 2, and illustrates the coöperation of the knives which constitute the cutting mechanism. Fig. 4 is a view taken along line 4—4 of Fig. 1, and illustrates the clenchers in plan view and the adjustable guide for the strip of tickets. Fig. 5 is a perspective view of one of the tickets, illustrating the staple therein positioned and clenched by the present mechanism. Fig. 6 is a horizontal sectional view taken along the line 6—6 of Fig. 1. Fig. 7 is a vertical section through the clenchers, and illustrates in dotted lines their closed positions.

Reference being had more particularly to the drawings, 10 indicates generally the

frame for the machine, provided with a 55 gooseneck 11, upon which is mounted a stapling head 12 of a standard construction.

A drive shaft 13 is mounted in the goose neck 11 and drives not only the stapling head 12, but also the clenching mechanism, 60 as will hereinafter be apparent.

A pulley 14 is mounted on the shaft 13 and is adapted to be connected thereto to rotate said shaft by the clutch indicated generally at 15, operable by the pedal 65 rod 16.

An eccentric 17 is keyed to the shaft 13, and is designed to operate the clenching mechanism.

A rod 18 is mounted for vertical reciprocation in the bearings 19 on the frame of the machine in direct vertical alinement with the eccentric 18. The upper end of this shaft is provided with a roller bearing 20, which is operated upon by the eccentric upon the 75 rotation thereof to reciprocate the rod 18 vertically. This rod is retained in a normally elevated position by the spring 21, which is interposed between the upper bracket or bearing 19 and the upper terminal of the rod 18, thereby normally holding the roller bearing 20 in constant contact with the eccentric 17.

A lever 22 is pivoted to the frame 10 of the machine at a point medial of its length 85 and is bifurcated as at 23 at its inner terminal for engagement with the lower end of the rod 18, so that as the rod 18 is reciprocated by the eccentric 17 the lever 22 will be oscillated about its pivotal point. The 90 outer terminal of the lever 22 is pivotally connected to a vertically reciprocable rod 24, which is designed to operate the clenchers. The mechanism which has just been described is the usual and standard construction, which forms parts of Patents Nos. 548,681, 683,821, 683,822, and 980,647, and forms no part of the present invention other than an operating mechanism therefor. The 95 connections and mounting of the rod 24 are 100 likewise of the usual and standard construction.

The upper terminal of this rod 24 extends through a bed plate 25, which is located directly under the stapling head 12, and is provided at its upper terminal with an offset hook or head 26. This hook or head 26 has roller bearings 27 thereon, which normally

rest horizontally and operate the clenchers to form the staple as shown in Fig. 5.

Upon the bed plate 25 of the machine and upon each side of the opening through which the head or hook 26 of the rod 24 reciprocates is a block 28, provided with the spaced offset portions 29, which are alined with the stapling head mechanism and which form a housing for the clenchers.

10 A bar 30 is secured or formed centrally to one of the offset portions 29 and abuts and rests flush in the plane of the opposite offset portion 29, said bar constituting the means whereby the legs L of the staple S are spaced when they are partially clenched to assume the positions shown in Fig. 5.

15 Pivoted upon each side of the bar 30 is a clencher 31, the outer face of which is inclined outwardly and upwardly and terminates at its lower end in a right angular arm 32.

20 Stops 33 are interposed between the offset portions 29 of the blocks 28 adjacent to the upper widened ends of the clenchers 31 and 25 against which said clenchers rest prior to any movement thereof toward the bar 30. The roller bearings 27 of the head or hook 26 operate against the inclined faces of the clenchers 31 and as the hook moves upwardly these roller bearings force the clenchers 31 toward the bar 30 until the inner faces of said clenchers rest approximately flush against the bar. The legs L of the staple after the same have pierced the ticket T rest 30 between the inner faces of the clenchers and the bar 30, so that when the clenchers are moved about their pivotal points toward the bar 30 said legs L of the staple S will be bent to the dotted line position Fig. 7, where 35

40 they rest flush against the bar 30. When the head or hook 26 moves downwardly the roller bearings 27 will contact with the arms 32 of the clenchers and swing the same outwardly until the upper terminals of the 45 clenchers will rest against the stops 33. In this manner the legs of the staple are partially clenched as illustrated in Fig. 5, leaving the major portions thereof unclenched so that they may pierce another section of 50 material and be clenched manually thereto.

55 The tickets are fed in a continuous strip T^a from the forward side of the machine over the upper edges of the offset portions 29 to the grooved guides 34 which are carried by the blocks 35 secured to the bed plate 25 of the machine, by bolts 36. These blocks are provided with the slots 37 through which the bolts 36 extend, thus providing for an adjustment of the blocks 35 to and from one 60 another so that tickets of various widths may be accommodated.

65 The continuous strip T^a extends to the cutting mechanism operable from the drive shaft 13, where the strip T^a is severed into 125 the individual tickets T. This cutting mech-

anism comprises a pair of shafts 38 and 39, interposed between which and mounted for reciprocation thereon is a frame 40. One side of this frame is provided with a set-screw 41, whereby the frame is locked in any of its adjusted positions. The shaft 39 is provided with a keyway 42, whereby oscillation imparted to said shaft will be transmitted to the cutting mechanism, as will be apparent. A grooved cam 43 is mounted upon the shaft 13 and is connected by a pitman 44, which coöperates with the groove of said cam and receives a vertical oscillation therefrom, to an arm 45 keyed to the free terminal of the shaft 39. Mounted upon the shaft 39 for reciprocation with the frame 40 is an arm 46, which is provided with a key 47 that is slidable in the keyway 42 of the shaft 39. On each side of the front of the frame 40 is a guide 48, between which guides 85 is mounted for reciprocation a lower knife 49. This knife is carried by a suitable block, which is connected to the free terminal of the arm 46. Consequently, as the shaft 39 is oscillated this knife 49 which is oblique, will 90 be moved upwardly to shear or separate the tickets in the strip T^a. An upper knife 50 is carried between the guides 48 adjacent the upper terminal of the frame and coöperates with the lower knife 49, as illustrated in 95 Fig. 3, to separate or cut the strip T^a.

In order to insure the proper contact of the legs L of the staple with the clenchers 31, the inner faces thereof are provided with the grooves 31^a, which receive the legs of the 100 staple. These grooves 31^a also extend across the upper ends of the clenchers to accommodate the portions of the legs of the staple already clenched.

I claim:

1. The combination with a stapling head, of clenchers coöperating therewith, stationary pivots for said clenchers and means for operating said clenchers to partially clamp a staple formed by said head and to form an 110 offset in the leg of said staple for fastening said staple to another article.

2. The combination with a stapling head adapted to form and drive a staple, into a continuous strip of tickets arranged to be fed to said stapling head, means for partially clamping a staple driven into said strip of tickets by said head, and a device for severing said strip into individual tickets, after the staples have been inserted therein and it has passed said stapling head, and means for adjusting said device relative to said head.

3. The combination with a stapling head adapted to form and drive a staple, into a continuous strip of tickets arranged to be fed to said stapling head, means for partially clamping a staple driven into said strip of tickets by said head, and adjustable means for severing said strip into individ- 130

ual tickets, after the staples have been inserted therein and the portion carrying the staples has been moved away from said head.

4. The combination with a stapling head 5 arranged to operate upon a continuous strip of material, a drive shaft for said stapling head, a rock shaft and means carried by said rock shaft and operable from said drive shaft for severing said strip of material into 10 sections.

5. The combination with a stapling head, of a drive shaft coöperating therewith, a rock shaft and a stationary shaft, a frame 15 mountable for reciprocation upon said rock shaft and said stationary shaft, cutting elements carried by said frame, and means for operating said cutting elements from said rock shaft.

6. The combination with a stapling head, 20 of a drive shaft therefor, a rock shaft, a frame adjustably mounted on said rock shaft, knives mounted in said frame, means for oscillating said rock shaft from said drive shaft, and a connection between said 25 rock shaft and said knives.

7. The combination with a stapling head, of a drive shaft therefor, a stationary shaft and a rock shaft, a frame adjustable on said stationary shaft and said rock shaft, knives 30 carried by said frame, means for oscillating said rock shaft from said drive shaft, and a constant connection between said rock shaft and said knives.

8. The combination with a stapling head, 35 of a partition coöperating therewith, clenchers having pivots arranged adjacent to said partition and in fixed relation thereto, and means for operating said clenchers to and

from said partition whereby the legs of a staple are partially clenched.

9. The combination with a stapling head, 40 of a partition coöperating therewith, a clencher pivoted on each side thereof, and a hook movable relative to said clenchers for moving said clenchers about their pivots to 45 and from the partition aforesaid.

10. The combination with a pair of pivoted clenchers, of a clencher rod recipro- 50 cale relative thereto, an abutment member and a connection between said clenchers and said rod whereby the clenchers are moved to and from said abutment member.

11. The combination with a pair of pivoted clenchers, of a partition interposed therebetween, and means for moving said 55 clenchers to and from said partition, said means including reciprocating cam rolls adapted to coöperate with said clenchers to alternately move said clenchers in opposite directions.

12. The combination with a pair of pivoted clenchers, of a partition interposed therebetween, and means movable relative to 60 said clenchers for oscillating said clenchers about their pivotal points so that their inner faces lie approximately flush with the partition aforesaid.

In testimony whereof I have signed my name to this specification, in the presence of two subscribing witnesses, on this 28th day 65 of July, A. D. 1914.

HENRY WEBER.
